MINE BLASTING AND SIMILAR
OPERATIONS

Walter Voortmann, Dortmund, Germany

Application May 23, 1935, Serial No. 23,105
In Germany February 16, 1934

3 Claims. (Cl. 102—5)

The present invention relates to a method of and means for mine blasting both above ground (quarrying) and under ground. Hitherto, the tamping of blasting holes has been based solely 5 on practical experience and has not taken into account the effect of rock pressure and the nature of the strata to be blasted. Consequently, for example, in coal mining, the coal has been largely shot to coal dust by the wrong tamping method 10 and by too heavy an explosive charge.

In the art of shot-firing, it has been appreciated for some time that if the utmost useful work is to be performed by the explosive, the high pressure gases released on firing the charge must 15 be confined in the bore hole and must be made to exert their maximum pressure on the rock, coal or other containing strata to be blasted. For this reason, stemming is used to confine the gaseous products in the bore hole until the pressure 20 generated is sufficient to burst the containing strata. Pressure also is important in effecting complete combustion of the solid explosive, thereby reducing the possibility of the production of fumes. Therefore, the stemming should be sufficiently 25 rigid to prevent it being blown out of the bore hole and the more rigid the stemming, the more effective is the explosive.

Although these desiderata have been well-known, they have not been achieved in practice 30 with the methods of stemming known up to the present, since with all these known methods the stemming at the beginning, immediately nearest to the charge, has been relatively loosely tamped in order to avoid damage to the priming cartridge 35 and it has been only remote from the charge, near the mouth of the bore hole, that the stemming has been at all tightly tamped. Consequently, when the charge is fired the high pressure gases dissipate some of their energy in 40 performing useless work in forcing back the beginning of the stemming and very often the stemming is unable to resist this pressure and is blown out of the bore hole. Even when the stemming resists the pressure of the gases some 45 part of the charge has been wasted in performing this useless work of compressing the stemming.

It is also already known to provide a blasting space or air cushion between the end, priming, 50 cartridge of the explosive charge and the stemming. This method of shot-firing is known as cushion firing and has advantages by reason of the fact that the air space "cushions" or reduces the violence of the explosion by distributing 55 it throughout the air space, instead of it being

localized at one spot. It has been found and is fully realized that, for most efficient results, the length of the air cushion should be varied according to the nature of the strata to be blasted, but with the present known practical methods of stemming, it has not been possible to control this length with any reasonable degree of accuracy. As yet, there is no known easy practical method of accurately controlling cushion firing.

The present invention has for its main object 10 to provide a new method of and means for tamping stemming; and further objects of the invention are a method and means for accurately controlling cushion firing; a method and means whereby a saving in the quantity of explosive 15 used is effected and an improved output of material is obtained by reducing the amount of dust formed; the elimination of flame; to render it practically impossible to have a blown-out shot; 20 to eliminate almost entirely the reek produced by the explosive; to render it impossible for the detonator to be exploded when the stemming is being tamped.

These objects are achieved by introducing into 25 the bore hole, after the charge has been inserted in the bottom of the bore hole, a stemming plug of incombustible material provided with a pulling member which extends outside the bore hole. The stemming plug is first pushed up against 30 the priming cartridge of the charge by means of the tamping tool which is inserted in the bore hole, then, while holding the pulling member attached to the plug against the tamping tool, the pulling member, if a cushion is required, is pulled 35 to withdraw the plug to leave a blasting space between the priming cartridge and the stemming plug. The length of this space or air cushion, if provided, is predetermined according to the nature of the rock or the like to be blasted and 40 is measured off by the distance by which the pulling member is withdrawn from the mouth of the bore hole. The tamping tool is then removed and a quantity of stemming inserted in the bore 45 hole and is tamped tightly against the plug with the stemming tool while at the same time the pulling member is held to maintain the plug in its correct position and afterwards pulled to force 50 the stemming round the base of the plug, thereby forming a gas-tight seal across the bore hole. The bore hole is then tamped with stemming in the normal manner. Afterwards the stemming is tested by pulling hard on the pulling member. 55 If the latter moves at all, thereby giving an indication that the plug has moved, more stem-

ming is required, but if the plug is firm the tamping is complete.

In this way the stemming and the air cushion, if provided, are accurately controlled by means of this stemming plug and pulling member. Furthermore, by means of the pulling member controllable from outside the bore hole, the stemming can be made completely rigid and gas-tight at the beginning and without any risk of the cartridge and detonator being crushed or damaged while the stemming is tamped. Thus, the advantages of accurately controlled firing are obtained.

It is an important feature of the invention that the plug may be firmly held by means of the pulling member at any definitely required distance from the end priming cartridge. When employing cushion firing, this distance is variable and depends upon the nature of the rock or the like to be blasted. The distance will, for instance, be greater with soft rock than with hard rock.

Also, the cartridges of the explosive charge will preferably be arranged directly one behind the other without intervening spaces so that they reach to the bottom of the bore hole.

The result will then be obtained that all the cartridges will be ignited. The gases from the explosive, which act in the cavity or air space between the end priming cartridge and plug, will then blast off a large coherent mass, which can easily be reduced as desired.

The invention also comprises a stemming plug for use in the above method, a preferred construction of which comprises a substantially cylindrical body of incombustible material of somewhat smaller diameter than the internal width of the bore hole in which it is to be used, the said plug having a central bore for accommodating a non-inflammable pulling cord or the like and having one or more lateral grooves through which pass the ignition wires or fuse of the priming cartridge.

A constructional example of the invention is illustrated diagrammatically, by way of example, in the accompanying drawing, in which Fig. 1 shows a lay-out of the charge in a bore hole according to the method of the invention.

Fig. 2 illustrates, on a larger scale, a stemming plug according to the invention adapted to be inserted in the bore hole.

Fig. 3 shows a view of the left end of the plug according to Fig. 2, also on a larger scale.

Fig. 4 shows, on a larger scale, cords of different lengths in combination with plugs according to the invention.

Fig. 5 shows, on a smaller scale, an arrangement of bore holes for carrying out the method according to the invention when blasting in a mine.

With reference to Fig. 1, a bore hole is bored into the rock to be blasted, the closed end of which bore hole accommodates explosive cartridges 1. As can be seen from the figure, the end cartridge at the left is located in the bottom of the bore hole and the other cartridges are so positioned as to succeed the latter without intervening spaces. The end cartridge at the right is the priming cartridge, from which ignition wires 2 lead to the open end of the bore hole. A plug 3, which is made of incombustible material, or of salt, and the length of which is about one and a half times its diameter, is introduced into the bore hole from the right in such a manner that a cavity H is left free between the end of

the priming cartridge and the left-hand end of the plug 3. The diameter of the plug is somewhat less than the internal width of the bore hole.

As can be seen from Figs. 2 and 3, the plug 3 is of substantially cylindrical form. It is provided with an axial bore, through which a cord 4 is passed. This cord is provided at the end located in the plug with a knot 4' which lies in a corresponding cavity 5 of the plug, said cavity 10 being curved (for instance, semi-spherical). The cylindrical outer surface of the plug is provided with a groove 6, through which pass the ignition wires 2.

Once the plug has been inserted in the bore hole in the manner illustrated in Fig. 1, part of the stemming B is first tamped against the plug, the plug being firmly held by the cord. The remainder of the stemming can then be tamped. There is no danger whatever of the striking priming cartridge being damaged by the tamping of the stemming, because after tamping the first part thereof, the plug is stationary. It can be checked from outside the bore hole by an inspection of the cord whether the plug has moved or not and also whether the stemming has been correctly tamped by pulling hard at the cord. If the cord and plug move at all, more stemming is required. If firm, the tamping is complete.

The cord consists of incombustible material 30 and is supplied in various lengths, in order to be able to use it for bore holes of different lengths. Preferably the end of the cord is coloured. For example, the different useful lengths such as 1.50 m., 1.60 m., 1.70 m., etc., are distinguished by 35 different colours.

As can be seen from Fig. 4, for instance, the cord of the top plug is longer than the rest. The colour of this cord is indicated by the interruption of the left-hand end of the cord. The 40 different marking of the cord of the centre plug is indicated by a chain-dotted line and the marking of the cord of the lower plug by a dotted line. When an electric current flows through the ignition wires 2, the priming cartridge is ignited, the 45 ignition flame is propagated with certainty up to the cartridge lying at the end of the bore hole, owing to the compact assemblage of the individual cartridges, the explosion wave of the powder gases returns to the cavity H and then 50 acts in the direction of least resistance. Any expulsion of gases is prevented by the tamping of the stemming. The stemming, particularly at the beginning, is also tamped so firmly in the bore hole that ejection of the stemming or the 55 plug is avoided.

Since the bore hole is sealed so as to be gas-tight neither gases or particles of explosive can escape when the explosion of the charge takes place. The whole of the explosive charge is used 60 up. Consequently the occurrence of the so-called after fumes is also prevented. The mine or quarry at which the blasting takes place can be entered again shortly after the explosion. Moreover, a coal dust explosion or ignition of explosive gases is prevented since the flame does not reach the exterior.

The size of the cavity H depends on the nature of the rock. The harder the rock, the smaller the size of the cavity.

In Fig. 5, for example, 7 denotes diagrammatically a mine being worked. 8 is a gallery in which a shaking conveyor 9 is arranged. At the right of the gallery 8 is a coal seam to be worked. Inclined blast holes 10, 11 and 12 are first bored 75

and by blasting, a recess or niche is worked out, as indicated by the chain-dotted line N. After the coal has been removed from this niche, blast-holes 13 and 14 are respectively bored. By further blasting of the seam with the explosive charge introduced into the bore hole 13, the block situated between the bore hole 13 and the wall of the niche is pushed out as a whole towards the niche and relieved of the rock pressure, so that only very little coal dust arises. Since the block shows fine fissures, it can be further reduced very easily. In the same manner the block of coal situated between the bore hole 14 and the niche is pushed out towards the niche by blasting. In this manner, by using a reduced quantity of explosive charge, coal may be obtained with a much smaller quantity of coal dust than hitherto, thus ensuring improved mining operations over those hitherto practised.

0 I claim:—

1. In blasting operations, the method of laying a blasting charge in a bore hole in which an incombustible plug having a diameter slightly less than that of the bore hole and a flexible holding member attached thereto is utilized, which comprises the steps of inserting the blasting charge into the bore hole, inserting said plug into the bore hole, tamping stemming material tightly against said plug while the latter is firmly held by said flexible holding means, against movement toward the charge, and then pulling the said plug outwardly by said holding means in order to insure the compactness of the inner portion of the stemming material.

2. In blasting, the method of laying a blasting charge in a bore hole in which an incombustible cylindrical plug having a diameter slightly less than that of the bore hole and a flexible holding member attached thereto is utilized, which comprises the steps of inserting a blasting charge into the inner end of a bore hole, inserting said plug into abutting relationship with said blasting charge, withdrawing said plug a predetermined distance by said flexible holding member so as to leave an air space between said charge and said plug and tamping a quantity of stemming material tightly against said plug while the latter is firmly held by said holding means against movement toward the charge, whereby a gas-tight and firm seal is formed.

3. The method of laying a blasting charge in a bore hole in which an incombustible cylindrical plug having a diameter slightly less than that of the bore hole and an elongated flexible holding member attached thereto is utilized, which comprises the steps of inserting the blasting charge into the inner end of the bore hole, inserting the plug into abutting relationship with said charge, drawing out the plug a predetermined distance from the blasting charge so as to leave a cushioning air space, forcing tamping material tightly against the plug while holding it firmly in place, and then pulling it outwardly by means of the flexible holding member so as to insure the compactness of the inner portion of the tamping.
